UNITED STATES PATENT OFFICE

GEORGE WILEY GARDNER AND JOHN RAYFORD UNDERHILL, OF GREENVILLE,
NORTH CAROLINA

FIRE HOSE HOIST

Application filed April 10, 1930. Serial No. 443,237.

This invention relates broadly to an improved hoist, guiding and retaining device for use in association with fire fighting equipment and apparatus.

5 The specific details and their relative arrangement and association will become more readily apparent from the following description and drawings.

In the drawings:

10 Figure 1 is an elevational view of the complete device showing it attached to a window sill construction representing the approximate manner of use,

Figure 2 is a top plan view thereof,

15 Figure 3 is a front end elevational view of the sill engaging hook device,

Figure 4 is a side elevational view of an extension frame,

20 Figure 5 is an end view of the clamping screw mount.

As seen in Figure 1 the invention comprises two primary parts; namely the outer hook device 6, and a complementary retaining device 7. The device 6 embodies a pair of spaced parallel side plates 8 of the side elevational configuration seen in Figure 1 having depending outer end portions terminating in retention hooks 9.

25 The numeral 10 designates bracing bolts and 11 designates a similar bolt which has the additional function of a hanger to accommodate retaining elements of the device 7. The numeral 12 designates a cross member between the lower hooked ends of the plates which is here shown provided with an apertured arm 13 constituting a guide for a hoisting rope (not shown). The numerals 14 and 15 designate concaved hose receiving and guiding rollers rotatably mounted on some of the bolts 10. Incidentally the hose is designated by the numeral 16 shown in dotted lines in Figure 1.

30 The device 7 comprises a pair of L-shaped metal straps of appropriate strength. The horizontal arm portions 17 are formed with longitudinally spaced teeth 18 to selectively engage the keeper or hanger bolt 11. Between the outer ends of the strap members 17 is a cross piece 19 which as seen in Fig-

ure 2 is provided with a fastener 20 adapted to engage an adjacent link of the chain 21.

This chain extends down over the rollers and has one end portion wrapped around the hose as indicated at 22 in Figure 1. The depending short arm 23 of the retainer 7 as seen in Figure 1 serves to support the clamping screw 24. This screw is threaded through a substantially U-shaped bracket 25 which is fastened to and spans the arm 23 as represented in Figure 5.

The screw is provided with a suitable knob or hand grip 26. The inner end is pointed so as to permit it to be bound tightly against the adjacent wall or other support in which the invention is placed. Thus, it will be seen by placing the device 6 over the outer sill and selectively engaging the rack teeth with the cross bar 11, the retainer 7 will be in a position to permit the screw 24 to be tightened against the inner wall of the building.

35 This permits the device to be firmly mounted on a window sill structure where it is in convenient position to aid in hoisting and guiding the hose 16 over the rollers 14 and 15. Whenever necessary or desired an additional guide roller 27 may be provided and this is mounted between the members 17 as shown in Figure 2. When it is desired to use the device on a support which is wider than the full length of the device composed of the parts 6 and 7, an extension frame 28 is used which includes the spaced parallel members 29 having terminal hooks 30. This extension member is interposed between the device 6 and the device 7 with its hooks 30 engaging the bar 11 and its cross piece 30' engaging a pair of the rack teeth 18 of the member 7.

40 In using the device the parts 6 and 7 are adjusted across a window sill as shown in Figure 1 or other support and the screw 24 turned to clamp the device in position. A cable is then passed through the eye of the arm 13 and the cable used to hoist hose, ladders or other fire equipment or objects to the window or other support. When the device is used in connection with a hose which is shown at 16 in Figure 1 the hose is pulled over the rollers 14 and 15 so that these roll-

ers will form guiding means for the hose and enable the hose to be easily handled without danger of injuring the hose on the corners of the window frame. The chain 21 will hold the hose in adjusted position while permitting a certain amount of movement of the same.

Minor changes in shape, size, and rearrangement of details coming within the field of invention claimed may be resorted to in actual practice if desired.

Having thus described our invention, what we claim as new is:

1. In a structure of the class described, in combination, an outer device embodying a pair of spaced parallel hooked plates, guiding rollers mounted for rotation therebetween, a retaining bolt carried by said plate, a retainer comprising a pair of spaced parallel L-shaped strap members, the horizontal arms of said members being provided with longitudinally spaced teeth engageable with said retainer bolt, and a binding screw carried by the depending arm portion of said strap.

2. In a structure of the class described, a retainer comprising a pair of substantially L-shaped spaced parallel metal straps, each strap including a horizontal long arm and a vertically arranged short arm, the horizontal long arms including longitudinally spaced retaining teeth, a U-shaped bracket carried by the lower ends of the short arms, a feed screw mounted in said bracket, and a roller mounted between said straps at the juncture of the long and short arms.

3. A device of the class described comprising a hook-shaped member, a roller carried thereby, an angle-shaped member, means for adjustably connecting one arm of the angle-shaped member to the shank of the hook-shaped member, a clamp screw carried by the other arm of the angle member, and a roller carried by the angle-shaped member at the juncture of the two arms thereof.

In testimony whereof we affix our signatures.

GEORGE WILEY GARDNER.
JOHN RAYFORD UNDERHILL.
